UNITED STATES PATENT OFFICE

RICHARD M. CRAIG, OF SAN ANTONIO, TEXAS

ILLUMINATED SIGN

Application filed August 6, 1929. Serial No. 383,907.

Owing to the delicate nature and fragility of neon and other luminescent tubes used in the manufacture and installation of signs for display purposes, considerable difficulty has been experienced in shipping or transporting the tubes from the factory to the point of installation. Furthermore, these tubes in the course of manufacture are generally bent, molded or twisted to form the letters of the word or sign to be displayed and, if, after the tubes are secured in position on the sign, a fracture or breakage occurs in one of the letters of the sign, it necessitates bodily removal of the sign, reshipment to the factory for repairs or replacement and a new installation of the repaired letters. As a result of the difficulty in shipping the delicate tubes from distant points to the place of installation, it has been found desirable, in fact, necessary, to equip a factory in the town or city where numerous signs are displayed. This necessarily entails considerable expense and, furthermore, requires a force of workmen constantly in attendance to remove and replace the tubes when they become broken, fractured or otherwise impaired.

The object of the present invention is to form neon or other luminescent tubes at the factory in standardized units, each unit consisting of a plurality of superposed folds or coils disposed in parallel relation and in intimate proximity to each other, each bank of folded or coiled tubes constituting a unit serving to display a word or a plurality of letters constituting one or more words. This result is accomplished by making a stencil and placing it over the luminescent tube units in such a manner that one or more of the words to be advertised or displayed will appear through the stencil at each unit. In other words, only portions of the tubes of each unit will be visible through the stencil forming the letters or words to be displayed, the remaining portion of the tubes of each unit being obscured by the opaque imperforate body of the stencil. In this manner, any desired wording or advertising may be made to appear on the sign by merely changing the nature or character of the stencil and with-

out the expense of blowing, bending or otherwise forming the tubes into the desired letters or characters as heretofore has been the practice. The sign may be changed every day by merely putting on a new stencil without the necessity of removing or in any wise disturbing the banks of tubes. Furthermore, inasmuch as the several banks of luminescent units are firmly secured to the background of the sign, liability of breakage or displacement of the units is reduced to a minimum, but should such breakage occur in any one of said units, it may be readily removed at a moment's notice by an unskilled workman and said damaged unit or units replaced without the necessity of shipping the sign to the factory for replacement of parts.

One embodiment of the invention is illustrated in the accompanying drawings and will be hereinafter fully described, the novel features being particularly pointed out in the appended claims.

In the drawings:

Figure 1 is a perspective view, with parts broken away, of a sign embodying the present invention,

Fig. 2 is a front elevation with the stencil plate removed,

Fig. 3 is a horizontal section on the line 3-3 of Fig. 2,

Fig. 4 is a detail perspective showing one of the illuminating units removed, and

Fig. 5 is a detail illustrating one effect produced when the sign is in use.

In carrying out the present invention, there is shown a base 1 upon which is mounted a motor 2 and a housing 3 within which is arranged gearing for rotating the sign, and electrical conductors and make and break devices for controlling the illumination. The mechanism includes a shaft 4 which is rotatably mounted in the upper portion of the housing and frame, indicated as an entirety by the numeral 3, and upon the front end of this shaft is secured a rotating head or support 5, said support being shown as a circular disk having a rim 6 around its margin and having partitions 7 extending across its outer surface, as indicated in Figs. 1 and 2, the disk and said partitions being of some opaque

non-conducting material. The disk or head is secured to the shaft through the medium of a junction box or hub 8 and the shaft is hollow to permit the wires carrying current to the illuminating tubes to pass through the shaft and to rotate with the shaft, brushes and collector rings being employed in a well known manner to establish the electric connection between the movable conductors and the stationary conductors. Removably secured upon the outer edge of the marginal rim 6 is a cap plate of stencil 9 having openings 10 formed therethrough, which openings are so arranged as to produce letters, words or other characters, the words "Flash 15 lite gas" being shown in the accompanying drawings by way of example.

Secured upon the disk 5 between the partitions 7 and between the partitions and the rim are luminescent tubes 11 which, in the present instance, are in the form of coils, each coil including a plurality of straight sections arranged closely together in parallelism and connected alternately at their opposite ends by bent elbow portions, as clearly shown. These tubes have their terminal electrodes 12 disposed entirely in alinement with the respective portions from which they extend and parallel with the adjacent section of the coil so that the entire tube may occupy a plane parallel with the face of the disk and no portion of the tube will have to pass through the disk in order to secure the tube in place. Neon tubes, as now made according to general practice, are shaped to form letters or words or other characters, and in order to mount them upon a support, the terminal electrodes or end portions are turned at a right angle to the plane of the support and pass through the support and are mounted upon springs or similar cushioning devices, this arrangement being deemed necessary in order to avoid fracture of the tubes which are very thin and are easily broken. It is also now generally considered that the tubes must be mounted in spring supports as slight vibration will cause the tubes to fracture, and it has been generally considered, in a practical sense, that neon tubes must be mounted in a fixed position and cannot be employed in revolving apparatus as they are very apt to shatter under centrifugal force. According to the present invention, the tubes are seated in blocks 13 of wood or other analogous material, which blocks are secured to the face of the disk, or to panels removably mounted thereon, and firmly held in place by being coated with a cement having a cellulose base and having the same coefficient of expansion as the luminescent tubes. This cement is applied over the seat of the several blocks so that the tubes will be seated in the cement and actual use has demonstrated that tubes thus supported will be very firmly held and

the disk upon which the tubes are mounted may be rotated with the tubes at a high speed without causing any breakage or dislocation of the tubes. Each tube unit is preferably mounted upon a panel 14 which is of a size and form to fit nearly within a division of the supporting head defined by the margin 6 and a partition 7 and removably held therein by screws or similar fastening devices 15 inserted through openings provided therefor at the corners of the panel to engage in the disk 5, as will be understood.

In the particular example of the invention shown in the drawings, the stencil or cap plate 9 has three words cut therein and the tube-supporting head is divided into three sections or compartments by the partitions 7, the parts being so arranged that each word in the stencil plate will be coordinated with one tube unit in the head. The units are illuminated electrically in the usual manner and are filled with a gas which will impart to the tube a distinctive color when lighted. The shaft 4 is rotated at a relatively high speed and the current to the several tube units is controlled by make and break devices operating at a lower speed and which may be of any approved arrangement and construction. An example of such mechanism may be seen in my copending application for patent Serial No. 383,908, filed simultaneously herewith. In my co-pending application as well as in the present application, the head carrying the lighted or illuminated tubes is rotated continuously thereby causing the letters of the words "Flash lite gas" to apparently intermingle and form an artistic geometrical figure or design and when the tubes are of different colors the artistic effect of the displayed design will be materially enhanced. At a certain period in the revolution of the head, the current is intermittently cut off and on and always at the same point of revolution of said head so that instead of the letters of the words forming a geometrical design, said words will be legibly displayed in a readable horizontal position. The luminescent tubes are free of afterglow so that they light and are extinguished instantly as the current is cut in or out and they operate only on alternating current so that, while the effect upon the eye is of a continuous light, actually the light is being rapidly turned on and off. If as previously stated, the make and break devices be in such position that the illumination of the tubes will occur only once during each revolution of the shaft and head and always occurs at the same point in the revolution, the persistency of vision in the eye causes the eye to retain the impression of the flash of illumination of the tubes until the ensuing flash occurs so that the eye will obtain the effect of a stationary sign having its words illuminated in reading position.

If, however, the make and break devices are so set that the illumination is continuous throughout the rotation of the shaft and head, the tubes will actually be very rapidly lighted and extinguished at successive points or positions in the rotation of the head but the persistency of vision in the eye causes the eye to retain the impression of the illumination in one position overlapping the illumination in a preceding and also in a succeeding position so that the effect upon the eye is of a plurality of lines disposed in various angular relations to the radii of the disk and overlapping each other so that a kaleidoscopic effect is obtained. The design is produced by the apparent overlapping of the light passing through the openings which form the characters in the stencil plate and, consequently, the designs produced by no two machines will be the same unless the characters in the stencil plates of the two machines are identical. A wide variety of effects can be obtained by introducing into the tubes different gases and also by forming the tubes of glass of different colors, the gases ordinarily employed in neon or luminescent tubes having the faculty of assuming color when the electric current is passed through them and the color of the gas may be modified by varying the color of the glass from which the tube is formed. It is also possible to vary the color produced by mixing the gases in a tube and by introducing mercury or other elements. The stencil openings in my device are uncovered or clear openings and a peculiar effect of the apparatus is an apparent creeping or rocking of the tubes which is an optical illusion due to the inability of the eye to follow rapid motion. This apparent rocking of the several tubes causes the lines of light issuing from the tubes to cross each other, as indicated at 16 in Fig. 5, the result being that the letters or other characters are apparently covered with a net of coarse mesh and consisting of intersecting lines of light. It is to be particularly noted that the present construction provides units which are standardized and may, therefore, be produced in any quantity without waiting for a special demand and these standardized units may be employed in any sign. If a tube should be broken, it is not necessary to take the sign out of commission, as a reserve supply of the standardized units may be kept on hand and in order to replace a broken unit it is necessary merely to remove the screws retaining the panel carrying that unit in place so that the panel and the unit may be withdrawn from the supporting head, a new unit quickly placed in position on the panel and the panel then reinserted and secured. It is also to be noted that the sign at any one location may be changed indefinitely without requiring it to be out of com-

mission for any protracted period of time and also without requiring a complete dismantling and rebuilding of the sign. To change the sign, all that is necessary is to remove the stencil or cap plate 9 and substitute therefor another cap plate having different characters formed therethrough. 70

By using a stencil in connection with the luminescent tubes, not only may the wording on the display sign be changed at will but the width of the letters or characters may be varied at will so as to permit the display of characters much wider than the diameter of the luminescent tubes. Moreover, when the letters of the word being displayed are made relatively wide, it will be impossible to distinguish the luminescent tubes through the openings in the stencil as all the observer will see is the delineation of the letters or characters in a brilliant light effect. 75 80 85

Having thus described the invention, I claim:

1. A changeable display device comprising a head rotatable about its own center as an axis, a luminescent tube secured upon said head, and a cap plate rotatable with the head fitted over the tube and having character-forming openings cut therethrough. 90

2. A changeable display device comprising a rotatable head, a luminescent tube removably mounted upon the head and consisting of a plurality of closely arranged substantially parallel sections connected at their opposite ends alternately, the electrode terminals of the tube being disposed entirely within the plane of said parallel sections of the tube, and a stencil plate secured upon the head over the tube. 95 100

3. A changeable display device comprising a head rotatable about its own center as an axis, a panel removably secured upon the head, a luminescent tube carried by said panel, and a stencil plate secured upon the head over the panel. 105

4. A changeable display device comprising a head rotatable about its own center as an axis and having a marginal rim, and a plurality of partitions whereby the partitions and the rim will define a plurality of compartments, a luminescent tube mounted in each of said compartments, and a stencil plate secured upon the rim and extending over the partitions and having character-forming openings cut therethrough coordinated with the respective compartments. 110 115 120

5. A changeable display device comprising a rotatable head having an outstanding marginal flange, a plurality of panels detachably secured to the display face of the head, a luminescent tube secured to each panel and disposed entirely within the lines of the flange, and a stencil plate detachably secured to the flange and covering the tubes. 125

6. A changeable display device comprising a head rotatable about its own center as an 130

axis, panels detachably secured to the display face of the head, a luminescent tube secured to each panel and bodily removable with the panel from the head, and an opaque cap plate removably secured to the head over the tubes and having character-forming openings cut therethrough.

7. A changeable display device comprising a head rotatable about its own center as an axis, a plurality of banks of luminescent tubes detachably secured to the head, and an opaque cap plate detachably secured to the head and having character-forming openings cut therethrough to permit the unobstructed light rays from each bank of tubes to be directly visible through the openings.

8. A changeable display device comprising a head rotatable about its own center as an axis, a plurality of panels detachably secured to the display face of the head, supports carried by the panels, luminescent tubes seated in said supports and bodily removable from the head with the panels, and an opaque stencil plate detachably secured to the head and covering the tubes.

9. A changeable display device comprising a rotatable head having an outstanding marginal flange, partitions extending across the display face of the head and connected with and of substantially the same width as the flange, removable panels detachably secured to the head between the partitions, a plurality of banks of luminescent tubes, one bank being permanently secured to each panel, and a cap plate detachably secured to the marginal flange of the head and covering the several banks of tubes, said cap plate having clear character-forming openings cut therethrough.

10. A changeable display device comprising a rotatable head, panels detachably secured to the display face of the head, a coiled luminescent tube secured to and carried by each panel with the terminals of each coil disposed parallel with the adjacent surface of the panel, and a cap plate detachably secured to the head and extending over the several tubes, said cap plate having character-forming openings cut therethrough opposite each coil.

11. A changeable sign comprising a head rotatable about its own center as an axis, a panel detachably secured to the front face of the head, a stencil plate disposed in front of and spaced from the panel, and a display unit comprising a luminescent tube bent into a coil parallel with the adjacent surface of the panel and permanently secured thereto at predetermined points to equalize the strain of centrifugal force when the head is rotated.

12. A changeable sign comprising a head and a stencil plate rotatable together about a common center in parallel planes, and a

luminous tube mounted on the head between said head and stencil plate and rotatable therewith.

In testimony whereof I affix my signature.
